Primary Examiner — Susan Moon Lee(74) *Attorney, Agent, or Firm* — Novick, Kim & Lee, PLLC; Jae Youn Kim(57) **CLAIM**

I claim the ornamental design for an incubator, as shown and described.

DESCRIPTION

FIG. 1 is a perspective view of an incubator showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 5 Drawing Sheets(56)
